UMBRELLA AND PARASOL HANDLE

Filed March 20, 1930

UNITED STATES PATENT OFFICE

EMIL WEBER, OF EVANSVILLE, INDIANA

UMBRELLA AND PARASOL HANDLE

Application filed March 20, 1930. Serial No. 437,404.

The object of my invention is to provide an improved lady's umbrella handle carrying, at a suitable point above the usual grip, a novel arrangement of concealed mirrors, rouge, and powder puff, thus combining with the umbrella or parasol in a neat, secure, and convenient form those toilet articles which ladies are ordinarily obliged to carry in their hand bags.

10 A practical embodiment of the invention is hereinafter described and claimed and shown in the accompanying drawings, in which:

Figure 1 is a front view, showing the closure for the rouge being open;

15 Fig. 2 is a view at right angles to Fig. 1, both closures being closed;

Fig. 3 is a longitudinal section, the powder puff and rouge pad being in position and the closures being closed;

20 Fig. 4 is a face view of the rouge pad; and

Fig. 5 is an edge view thereof.

The embodiment shown and hereinafter described is subject to modification, as the 25 different articles comprising the "compact" may assume different forms from those disclosed, and the shape of the umbrella or parasol handle may be varied.

In the embodiment disclosed, the handle 30 has a lower part constituting the grip 1 and the upper part 2 which is constructed in accordance with the present invention and whose upper end has a socket 3 which receives the stem or pole 4 of the umbrella or parasol.

As shown, the part 2 of the handle is provided with cavities 5, 6 which may lie opposite to each other, or otherwise.

40 In one of the cavities, 5, there is a removable powder puff 7 of any preferred form and kind.

In the other cavity, 6, there is a removable disc or pad of rouge 8 which is provided on its rear with suitable clips 9, adapted to be 45 received in sockets or a circular cavity 10', whereby the rouge pad 8 is removably, yet securely, held within the cavity 6.

The closures 10 are provided on their inner faces with mirrors 11, and they cover the 50 cavities 5, 6 and prevent the powder puff 7

and rouge pad 8 from falling out of their cavities.

The closures 10 may be hinged as shown at 12 so that they may be swung open or closed and they are adapted to snugly engage the 55 handle 2, or, they may be provided with screw threads (not shown), engaging similar threads on the handle, or, they may be attached to the handle in any desired manner.

When one of the closures 10 is swung open, 60 the mirror 11 is conveniently arranged for use and access is afforded to the cavity closed by said closure.

If the rouge disc 8 is desired to be used, the closure covering the cavity 6 is swung outwardly. Should it be desired to use the powder puff 7, the closure for the cavity 5 is 65 swung open; if both the powder puff and the rouge disc are needed, both closures 10 are swung open.

The powder puff 7 is loosely received in the cavity 5 but the rouge disc 8 is held by its clips 9 in the cavity 6 although it can be removed when desired. When the rouge disc 8 is worn down to its backing, it may be completely removed and a fresh disc substituted. 75

What I claim is:

A handle provided with a cavity having a recess in its wall, and a spring-retaining-clip mounted on a removable article and 80 frictionally received within said recess to retain the article within the cavity.

In testimony whereof I affix my signature.

EMIL WEBER.
